UNITED STATES PATENT OFFICE.

MORRIS P. BRAY, OF ANSONIA, CONNECTICUT, ASSIGNOR OF ONE-HALF TO
AUGUST FELLHEIMER, OF NEW YORK, N. Y.

CORSET.

SPECIFICATION forming part of Letters Patent No. 412,015, dated October 1, 1889.

Application filed June 17, 1889. Serial No. 314,526. (No model.)

To all whom it may concern:

Be it known that I, MORRIS P. BRAY, of Ansonia, in the county of New Haven and State of Connecticut, have invented new Im-
5 provements in Corsets; and I do hereby de-
clare the following, when taken in connec-
tion with accompanying drawings and the let-
ters of reference marked thereon, to be a full,
10 clear, and exact description of the same, and
which said drawings constitute part of this
specification, and represent, in—

Figure 1, a side view of a corset embodying
the invention; Fig. 2, a rear view of one-half
15 the corset; Fig. 3, a vertical central section
cutting through the pocket; Fig. 4, a trans-
verse section cutting through the pocket.

This invention relates to an improvement
in that class of corsets which are provided
20 with shoulder-straps. In the more general
construction of this class of corsets the straps
are attached to or made an integral part of
the rear portion of the corset, and extend
over the shoulder and attached to the upper
25 end of the corset at the front. This attach-
ment, for convenience, is made so that the
strap may be detached for putting on or re-
moval of the corset, and should be so made
as to make it adjustable. In some cases the
30 straps extend from the front over the shoul-
der, and are in like manner connected to the
top of the corset at the rear. This brings
the strain upon the corset directly at the
shoulders.

The object of my invention is to take the
35 strain off the shoulder-straps at the rear and
at a point below the waist-line, so as to leave
the corset substantially free above.

To that end the invention consists in con-
structing the corset with vertical pockets near
40 the rear edges, and extending from near the
bottom of the corset to the top or nearly to
the top of the same, the pockets open at the
top and bottom, combined with straps extend-
ing from the front over the shoulder down
45 through said pocket, and with a detachable
securing device between the straps and cor-
set below the lower open end of the pocket.

The general cut of the corset otherwise than
the shoulder-straps and connection is imma-
50 terial.

A represents the strap, which is secured to
the front of the corset, or may be made as an
integral part of one or more of the portions
of the front of the corset, and extends there-
from so as to pass over the shoulder of the 55
wearer. On the rear of the corset, and near
the rear edge, a pocket B is formed, of a length
extending from near the bottom of the corset
upward to or near to the top, the pocket be-
ing open both at top and bottom. The width 60
of this pocket corresponds to the width of the
strap, and so that the strap may pass entirely
through the pocket and project below, where
it is adjustably attached to the corset, (here
represented as by a button C,) the strap being 65
provided with one or more button-holes D.
By this construction the lifting or supporting
strain of the strap is taken from a point on the
back below the waist-line, and so as to leave
the corset free around the waist-line and 70
above, so far as the strain or pull of the strap
is concerned; also, the adjustable connections
between the straps and the corset are carried
to a point so far below the waist-line as not to
interfere with the dress of the wearer, as 75
must always be the case to a greater or less
extent where the strap is secured near the
top and at the rear.

The portion of the strap which runs through
the pocket may be and is preferably made 80
from webbing and the shoulder-strap stitched
thereto, as shown; but the strap may be in a
continuous strip, if desired.

It will be understood that a like pocket is
provided on each side, one for each strap. 85

I claim—

A corset constructed with vertical pockets
on the rear and near the rear edges, the said
pockets extending from near the bottom up-
ward toward the top and open at the top and 90
bottom, combined with shoulder-straps ex-
tending from the front over the shoulders and
down through said pockets, with an adjusta-
ble attaching device between the straps and
the corset below the lower ends of the pockets, 95
substantially as described.

MORRIS P. BRAY.
